FOLDABLE DESK

Jonathan Ginat, New York, N.Y., assignor to Maurice Duchin Creations, Inc., New York, N.Y., a corporation of New York

Filed Feb. 7, 1964, Ser. No. 78,559

Term of patent 14 years

(Cl. D33—7)

I claim:

The ornamental design for a foldable desk, as shown.
